UNITED STATES PATENT OFFICE.

AUGUSTUS F. HARTER, OF CHICAGO, ILLINOIS, ASSIGNOR TO CRIBBEN & SEXTON COMPANY, OF CHICAGO, ILLINOIS, A CORPORATION OF ILLINOIS.

COMBINED COAL AND GAS RANGE.

1,209,288.

Specification of Letters Patent. Patented Dec. 19, 1916.

Application filed August 21, 1914. Serial No. 857,826.

To all whom it may concern:

Be it known that I, AUGUSTUS F. HARTER, a citizen of the United States, residing at Chicago, county of Cook, and State of Illinois, have invented a certain new and useful Improvement in Combined Coal and Gas Ranges, and declare the following to be a full, clear, and exact description of the same, such as will enable others skilled in the art 10 to which it pertains to make and use the same, reference being had to the accompanying drawings, which form a part of this specification.

My invention has for its object to make it 15 possible to heat the oven of a coal range by means of gas in an efficient manner, without interfering with the efficiency of the oven when coal is being burned, without greatly altering the construction of the range, and 20 without making it difficult or inconvenient to change from coal-heat to gas-heat.

The various features of novelty whereby my invention is characterized will hereinafter be described with particularity in the 25 claims; but, for a full understanding of my invention and of its object and advantages, reference may be had to the following detailed description taken in connection with the accompanying drawings, wherein:

30 Figure 1 is a front view of a well known type of coal range modified in accordance with my invention, parts being broken away to show the other parts normally hidden thereby; Fig. 2 is a section on line 2—2 of Fig. 1; Fig. 3 is a section on line 3—3 of Fig. 2; Fig. 4 is a perspective view of a closing device for the gas chamber; Fig. 5 is a section on line 5—5 of Fig. 1; and Fig. 6 is a top plan view of the oven plate used 40 when burning gas, parts being broken away.

Referring to the drawings, 1 represents a coal range having the usual oven, 2. The wall, 3, of the oven next to the fire pot, has removed therefrom a section extending from 45 the front toward the back just above the bottom wall, 4, of the oven; thus providing an opening, 5, a few inches high extending approximately throughout the depth of the oven. Outside of the wall, 3, in the ash pit, 50 6, is a casting, 7, forming with the wall, 3, a small chamber, 8, extending from the front to the back and communicating at the upper end with the oven through the opening, 5. The casting, 7, may conveniently be provided with a flange, 9, which extends through

the extreme upper portion of the opening, 5, and projects into the oven so as to form a ledge just above the effective portion of the opening, 5. The exterior of the wall, 3, below the opening, 5, and the interior of the casting, 7, are preferably lined with asbestos or the like, as indicated at 10 and 11. The casting is preferably so shaped that it curves gradually inwardly toward the oven toward its upper end. In the lower portion of the casting, 7, is a door, 12, extending approximately throughout the length thereof. The chamber, 8, is in communication with the outside atmosphere through the openings, 13, cut through the bottom wall, 14, of the range.

Beneath the range is a gas-supplying pipe, 15, screwed into a head, 16, which is secured to the bottom of the range just below the front end of the chamber, 8, and has its outlet end projecting upwardly through one of the openings in the bottom of the chamber. An elongated burner, 17, lies within the chamber, 8, and has its inlet end fitted loosely over the outlet end of the head, 16. A series 75 of lugs, 18, projecting from the bottom and side walls of the chamber, 8, engage with the rear end of the burner and hold it loosely in a predetermined position while permitting it to be lifted and withdrawn through 80 the opening controlled by the door, 12.

In the front wall of the range, at the end of the chamber, 8, is a small opening, 19, serving as an ignition opening through which the burner may be lighted when the 90 gas is turned on. Above the opening is a second opening, 20, covered with mica, this opening serving as a window through which the condition of the flame given by the burner can be seen without opening the oven 95 door, 21. It will now be seen that the curved upper portion of the casting, 7, serves to deflect the burning gases gently but positively so as to cause them to flow through the opening, 5, when the burner is 100 lighted, with the result that when the hot gases enter the oven they are traveling parallel with the bottom of the oven.

Adapted to be detachably placed in the oven is a hollow oven plate which may 105 conveniently be made of a casting, 22, having at one end a flange, 23, adapted to rest upon the ledge or flange, 9, and a bottom member, 24, of asbestos or the like adapted to rest upon the bottom of the oven. At 110

the edge of the member, 22, opposite that at which the flange, 23, is located is a downwardly projecting, perforated foot flange 25 adapted to rest upon the bottom of the oven. 5 Along the front of the casting, 22, is a depending, imperforate foot flange, 26; while at the rear is a similar short flange, 27, extending only part way from the edge provided with the flange toward the opposite 10 edge. The member, 22, may also be provided with downwardly-projecting lugs, 28 and 29, serving as spacers between the members 22 and 24; while suitable bolts, 30, serve to connect the two members together into a 15 single unit. The under side of the member, 22, for a considerable distance from the edge with the flange, 23, is preferably lined with asbestos, as indicated at 31.

An angle plate, 32, one member of which 20 is short enough to pass through the opening, 5, in the oven while the other member is slightly larger, is adapted to be placed in the opening, 5, to cover the same when the oven is being heated with coal. To do this, 25 the detachable oven plate is removed, and the cover plate is then inserted through the oven, the shorter member being passed through the opening, 5, as indicated on dotted lines in Fig. 3; whereupon, upon letting go of the cover plate, it positions itself by gravity with its larger member completely closing the opening, 5.

The top wall of the oven is made hollow 30 so as to provide a broad, shallow chamber, 33, extending from near the front of the oven to its back where it communicates with the main draft flue, 34. A damper, 35, controls communication between the chamber, 33, and the flue, 34. The chamber, 33, communicates with the interior of the oven through a series of perforations, 36, near the front of the chamber.

When coal is being burned, the oven plate 45 is removed, the cover plate, 32, is placed in position and the damper, 35, is closed. When it is desired to burn gas, the cover plate, 32, is removed, the oven plate is laid into the oven and the damper, 35, is opened. The burner is then ignited through the 50 opening, 19, and the flow of gas is regulated until the flame seen through the window, 20, is of the character desired. The hot gases flow out of the combustion chamber, 8, and into the oven plate; the foot flange at the front preventing the gases from rising into the oven along the front thereof; and the short foot flange at the rear making it necessary for the gases to travel toward the 55 middle of the oven, at the rear, before they are free to rise. The hot gases are therefore carried to points remote from the burner before they rise into the oven above the oven plate, and they must then travel toward the front of the oven before they can pass into 60 the combined outlet and heating chamber in

the top wall of the oven. The result is that an even, uniform distribution of heat is obtained and, because of the long paths which the gases must follow before being finally discharged from the oven and the chamber 70 in its top wall, a maximum amount of heat will be given up by the gases before they escape.

There is another feature of invention to which I have not referred. The supply 75 pipe, 15, for the gas and the connections thereto lie below the lowermost points on the range when the legs of the range are removed and are therefore in danger of being injured through careless handling of the 80 range. In accordance with my invention, I provide the bottom of the range with several short permanent legs, 40, sufficiently long to take the weight of the range when the main legs are taken off, but not long enough to be 85 in the way at other times. This insures the gas piping and connections against injury when the main legs are taken off.

While I have illustrated and described in detail only a single preferred form of my 90 invention, I do not desire to be limited to the exact structural details thus illustrated and described; but intend to cover all forms and arrangements which come within the definitions of my invention constituting the 95 appended claims.

I claim:

1. In a combined coal and gas range, an oven having an elongated opening extending through the wall into the ash pit adjacent to the bottom of the oven, an outwardly and downwardly curved wall extending from the top of said opening to the bottom of the ash pit and forming a combustion chamber, the latter wall having a flange 100 extending through the top of said opening and projecting into the oven.

2. In a combined coal and gas range, an oven having an elongated opening extending through the wall into the ash pit adjacent to the bottom of the oven, an outwardly and downwardly curved wall extending from the top of said opening to the bottom of the ash pit and forming a combustion chamber, the latter wall having a 110 flange extending through the top of said opening and projecting into the oven, a burner in the said combustion chamber, and an oven plate engaging with the aforesaid flange for directing the hot gases from said 115 chamber along the bottom of the oven.

3. The combination with a coal range, of a combustion chamber formed out of the lower corner of the ash pit adjacent to the oven, there being an opening leading from the upper portion of the chamber into the oven just above the oven bottom, and an oven plate comprising a heat insulating member adapted to rest upon and cover the oven bottom and an upper member lying above 120

the other member and adapted to extend from the wall of the oven just above said opening almost across the oven, and said chamber having therein a door leading to the ash pit and large enough to permit the insertion and removal of the burner therethrough.

4. The combination with a coal range, of a combustion chamber formed out of the lower corner of the ash pit adjacent to the oven, there being an opening leading from the upper portion of the chamber into the oven just above the oven bottom, and an oven plate comprising a heat insulating member adapted to rest upon and cover the oven bottom and an upper member lying above the other member and adapted to extend from the wall of the oven just above said opening almost across the oven.

5. The combination with a coal range, of a combustion chamber formed out of the lower corner of the ash pit adjacent to the oven, there being an opening leading from the upper portion of the chamber into the oven just above the oven bottom, and an oven plate comprising a heat insulating member adapted to rest upon and cover the oven bottom and an upper member lying above the other member and adapted to extend from the wall of the oven just above said opening almost across the oven.

from the wall of the oven just above said 30 opening almost across the oven, said upper member having an imperforate foot flange along the front edge and adapted to rest on the oven bottom.

6. The combination with a coal range, of a 35 combustion chamber formed out of the lower corner of the ash pit adjacent to the oven, there being an opening leading from the upper portion of the chamber into the oven just above the oven bottom, and an oven 40 plate comprising a heat insulating member adapted to rest upon and cover the oven bottom and an upper member lying above the other member and adapted to extend from the wall of the oven just above said 45 opening almost across the oven, said upper member having an imperforate foot flange along the front edge and adapted to rest on the oven bottom, said upper member having also a similar foot flange extending along 50 the rear edge for a considerable distance from the edge next to said opening.

In testimony whereof, I sign this specification in the presence of two witnesses.

AUGUSTUS F. HARTER.
